UNITED STATES PATENT OFFICE.

BENJAMIN FORSTER, OF MIDDLETOWN, CONNECTICUT, ASSIGNOR TO JAMES K. LANNING,
OF BOSTON, MASSACHUSETTS.

STOP-MOTION FOR LOOMS.

No. 888,796.

Specification of Letters Patent.

Patented May 26, 1908.

Application filed March 14, 1907. Serial No. 362,303.

To all whom it may concern.

Be it known that I, BENJAMIN FORSTER, a citizen of the United States, residing at Middletown, in the county of Middlesex and State 5 of Connecticut, have invented certain new and useful Improvements in Stop-Motions for Looms; and I do declare the following to be a full, clear, and exact description of the invention, such as will enable others skilled 10 in the art to which it appertains to make and use the same.

This invention relates to stop mechanism for looms, and has for its object to provide a device of this kind which will automatically 15 close an electrical circuit and thereby actuate the stop controlling mechanism of the loom whenever any of the threads of the warp are broken.

The device is extremely simple and can be 20 made very cheaply, and is so constructed that all parts of it can be seen without requiring any portion of it to be taken apart or separated. It can be placed in any position that is suitable for two or more harness and 25 can be set close to the harness, and the weight of the drops or warp detectors is not entirely borne by the warp threads, and if any of the threads are to be tied in the drops 30 they do not have to be taken from the drop that holds them while being tied. They act very quickly and whenever one of them has been actuated it will move into a position in which it can be quickly and readily located, thereby permitting of the thread being tied 35 with but little loss of time.

In the accompanying drawings which illustrate the invention, Figure 1 is a side elevation of a loom frame provided with my improved stop mechanism; Fig. 2 is an enlarged 40 view of one of the drops and the parts of the loom adjacent thereto; Fig. 3 is a top plan view of a portion of the loom showing the shipping mechanism in the position it occupies when the loom is running; and Fig. 4 is 45 a similar view showing the position of the lever after the loom has been stopped.

Referring more particularly to the drawings, 1 indicates the loom frame which may be of any desired construction provided with 50 the usual shipping lever, 2.

Suitably secured at each side of the loom is a fiber reed holder, 3, only one of which is shown as they are both alike, and are adapted to be secured in any convenient place adja- 55 cent to the harness, 4. Extending from one

holder, 3, to the other are front and back lease rods, 5 and 6, over which the warp threads, 7, are passed in the usual manner. Above the rods 5 and 6, are two wires, 8 and 9, on the lower one of which are pivotally 60 mounted the drops or warp detectors, 10, the lower portion of each of which is slotted longitudinally as at 11 for engaging with the cross portions of the threads, 7, between the lease rods if desired, and the upper portions 65 are adapted to engage with the upper wire, 9. These drops are preferably formed from flat steel, eight one thousandths part of an inch in thickness by seven-sixteenths of an inch in width, and substantially four and one-half 70 inches long, and when supported by the threads, they occupy an angle of about forty-five degrees, although it is evident that the size of the drops may be varied to suit conditions, as also the angle at which they are held 75 out of the vertical.

A source of electrical energy, as a battery, 12, is connected with the loom frame and thereby with the shipping handle, 2, by means of a wire, 13, and also with one of the 80 rods, as 9, by means of a wire, 14. A wire, 15, from the other wire, as 8, leads to an electro-magnet, 16, which is located in a position adjacent to the shipper handle, 2. The other end of the magnet is connected 85 with a spring, 17, by means of a wire, 18, whereby whenever anyone of the drops, 10, is permitted to fall into a vertical position by the breaking of either one of the wires with which its slotted end engages, the upper end 90 of the wire will engage with the upper wire, 8, and thereby complete a circuit and cause the magnet, 16, to be energized. As soon as the magnet has thus been energized, its armature, 19, is swung upon its pivot, 20, so as 95 to cause its free end to be moved into a position to be engaged by the lay, 21, the lay being preferably provided with a wearing plate, 22, to prevent injury when it engages with the end of the armature, 19. The 100 armature is preferably in the form of an elbow and is adjusted as by means of a set screw, 2', in the lever, 2, and which is adapted to engage with the depending end of the armature. When the parts are thrown 105 into this position by the breaking of a thread, as soon as the lay is moved forward to beat up the filling, it will engage with the armature and force the shipping handle, 2, out of its notch, 23, thereby allowing it to be thrown 110

to the opposite end of the slot, 24, and the loom to be stopped. As the spring, 17, forms a part of the circuit, it is evident that it will be impossible to start the loom so long as any thread is broken, and the circuit is complete at that point, for as soon as the handle 2 engages with the spring, 17, the circuit is complete at that point, and the magnet is energized, which will cause its armature to be raised and thereby prevent the handle entering the notch, 23, the spring being insulated from the rest of the loom frame. As soon as the lever has been disengaged from the notch, and is thrown to the opposite end of its slot in the usual manner, the circuit is broken and there is no loss of battery power even though the thread should not be tied immediately.

Although I have shown what I consider the most desirable means for embodying my invention, it is evident that changes and alterations can be made therein and I reserve the right to make all such variations as will come within the scope of my invention.

Having described my invention, I claim: 25
In a stop mechanism for looms, a loom provided with a lay, drop wires, an electromagnet; a shipper lever and an insulated spring bearing against the lever in its set position, an electrical circuit including said 30 wires, magnet, lever and spring, an L-shaped armature pivotally secured to the lever at its bend, one arm of the armature being adjacent to the magnet and being adapted to be moved thereby into the path of the lay to 35 engage therewith and throw off the shipper lever, and the other arm depending adjacent to said lever, and an adjusting screw in the lever in position for engaging with said 40 depending arm.

In testimony whereof I have hereunto set my hand in presence of two subscribing witnesses.

BENJAMIN FORSTER.
